ELECTROMAGNETIC MECHANISM

Joseph W. Allen, East Orange, N. J., assignor to
Bendix Aviation Corporation, South Bend, Ind.,
a corporation of Delaware

Application January 22, 1941, Serial No. 375,505

2 Claims. (Cl. 175—341)

This invention relates to electro-magnetic mechanism, and more particularly to electro-magnetic mechanism of the "solenoid" type, so-called, in which the magnetic circuit includes a closeable gap located within a current receiving winding, or coil.

In the accompanying drawing the invention is shown in an embodiment which has been favorably received for use as part of a system of control of the energization of an electric motor of the type employed in starting mechanism for internal combustion engines; but of course the accompanying drawing is illustrative only, and is not intended as a definition of the limits of the invention, reference being had to the appended claims for this purpose.

To a certain extent the illustrated embodiment follows the pattern of the solenoid switch mechanism disclosed in Patent No. 1,803,908 granted to Raymond P. Lansing on May 5, 1931. The departures from the Lansing disclosure will be described in detail, as they embody the novel features of the present invention.

It is an object of the present invention to provide a solenoid switch which is positive in action, but which operates with small current consumption.

It is another object of the invention to provide such a device which embodies a release spring amply strong to insure a positive, quick break under all circumstances.

Another object is to provide a device of the above character which is designed to have a highly efficient magnetic circuit, causing firm effective contact without undue current consumption.

A further object is the provision of such a device which is comparatively small and light so as to provide a quick, clean break of the contacts.

Another object is the provision of such a device which is inexpensive to manufacture, and in which the parts may be readily assembled or removed for inspection or replacement.

Other objects and advantages will be apparent from the following description taken in connection with the disclosure in the accompanying drawing.

In the drawing,

Fig. 1 is a longitudinal sectional view of a device embodying the invention;

Fig. 2 is an end view;

Fig. 3 is a view in perspective of a sub-assembly; and

Fig. 4 is a sectional view along the line 4—4 of Fig. 2.

Referring first to Fig. 1 of the drawing, numeral 10 indicates a cup-shaped shell or casing member preferably formed as a steel stamping. The member 10 is closed at its open end by a plate 11 which extends laterally therefrom and is provided with arms 12 forming a bracket by which the switch may be mounted in any desired location, such as a motor or upon any other part to be associated therewith.

A terminal plate 13 of non-magnetic material is secured on the outer face of the closure plate 11 by suitable means such as screws 14 which traverse the two plates and are threaded into the shell 10 (see Fig. 4) to hold the parts in assembled relation. Terminal plate 13 is provided centrally thereof with an outwardly projecting portion 15 having a pair of angularly related openings in which terminal members 17 and 18 are mounted. These terminal members are in the form of threaded bolts of good conducting material, such as copper or brass, having heads 19 and 20 which act as the stationary contacts of the switch. Suitable nuts 21, 22, are threaded onto the outer portions of the bolts for securing the same to the terminal plate and for attaching the conductors (not shown) to said bolts. Suitable insulating washers are interposed between the terminal plate and the heads and nuts of the terminal members 17 and 18, as shown, in order to prevent electrical contact thereof with the terminal plate.

The closure plate 11 is provided with a central opening, and a guide member 25 is mounted with its outer end suitably fixed in said opening as by means of the lip 26 expanded therein. The member 25 extends inwardly from the closure plate into shell 10 concentrically therewith, and constitutes a fixed magnetic pole piece for the solenoid. A connecting member in the form of a rod 27 of non-magnetic material is mounted to slide freely within guide member and pole piece 25, and is provided at its outer end with a contact plate 28 which may be swiveled thereon and is insulated therefrom in any suitable way as by means of the insulating material 29 in which said contact plate is imbedded. Contact plate 28 is located intermediate terminal heads 19 and 20 and closure plate 11, and is adapted to contact evenly with said heads 19 and 20, to connect electrically the terminal members 17 and 18 when the rod 27 is moved upwardly, as viewed in Fig. 1.

Connecting member 27 carries on the end thereof which extends into shell 10 a plunger 30 of magnetic material having a slightly smaller

diameter than the outside diameter of guide member 25. The plunger is suitably fixed to said connecting member as by means of a pin 48 (Fig. 3) and serves as a movable pole piece to cooperate with the fixed pole piece 25.

A spool 33 of suitable insulating material is located within the shell 10, and is adapted to fit closely within said shell and around the guide member and pole piece 25 on the closure plate 11. Spool 33 carries a solenoid winding 34 having terminal posts 35 and 36 which extend outwardly through openings in the shell member 10, and are insulated from the shell by means of suitable bushings 39 and 40. Terminals 35 and 36 are fixed to the inner head of spool 33 in any suitable way as by being locked or molded therein, and are clamped in assembled position by suitable nuts 41, which bear on bushings 39 and 40 and thus securely hold the spool 33 within shell 10. Conductors (not shown) may be clamped to the terminal posts 35 and 36 by suitable means such as nuts 46.

In lieu of extending the shell 10 to form a pocket of magnetic material for telescopic relationship with the pole piece 30—as is done in the construction shown in the Lansing patent, the construction shown in the above referred to—I employ two additional elements 38 and 31, the element 38 being thicker and the element 31 thinner than the shell 10. The thicker element 38, of magnetic material (preferably magnet steel such as, for example, the cobalt steel referred to in General Electric Company's U. S. patent to Harold T. Faus, No. 1,804,330, at page 1, line 58) closely surrounds the pole piece 30 and extends inwardly from the base of shell 10 (to which it is integrated, as by welding or riveting) for a considerable distance, wherefore there is assured—and without any reliance whatever upon the element 31—good magnetic continuity at all times from the shell 10 to the pole piece 30, by way of said magnetic sleeve 38, and regardless of whether the said pole piece is in circuit-opening or circuit-closing position. Because of this magnetic sleeve 38, therefore, the closure element 31 does not need to serve as a part of the magnetic circuit, and can accordingly be constructed of any thin, easily stamped metal, whether magnetic or not, but preferably an aluminum alloy of light weight; and it can be held in position by members 39 and 40, which engage the outer rim thereof, as shown.

Another departure from the construction shown in the Lansing patent is the transfer of the spring 32 to the end of plunger 21, beyond the contact-piece 28, wherefore it may be adjustable from time to time, as desired, by turning the adjusting screw 84 which bears upon said spring, and cooperates with a nut 85 and an outer cylinder 86 fixed to the cover plate 15 and extending around the spring, to protect the latter as well as to form the thrust absorbing element of the spring assembly.

When the control circuit through the solenoid winding 34 is closed by the operator in any suit-

able manner (as by means of a remote control switch located on the dash of the vehicle on which the unit may be installed) the magnetic flux produced in said winding 34 will move the plunger 30 upward as viewed in Fig. 1, compressing the spring 32 and moving the contact plate 28 into intimate engagement with the terminal heads 19 and 20 of the controlled circuit. This closes said circuit and causes the operation 10 of the motor or other part to be energized. When the control switch is opened by the operator, the magnetic flux of the solenoid drops almost instantly to zero, and spring 32 instantly and forcibly retracts the rod 21, carrying contact plate 28 away from the terminal heads 19 and 20 in spite of any burning together of the surfaces thereof which may have taken place, and so rapidly that any appreciable amount of arcing is prevented.

To facilitate sliding of plunger 30 within the auxiliary stationary pole-piece 30, I provide a thin sleeve 82 to fit closely between the elements 38 and 30; this sleeve 82 being of a metal other than steel, so that there will be minimum friction between the moving and stationary parts. This use of a different metal will not materially affect the magnetic efficiency of the device, however, as the sleeve 82 is very thin and is held to the plunger 30 by the steel pin 48 whose ends extend through the wall of the sleeve 82 and thereby effect magnetic continuity by direct contact with pole-piece 30, thereby tending to offset any slight loss in magnetic alertness that might otherwise result from the presence of friction-reducing sleeve 82.

What is claimed is:

1. In a solenoid, a magnetic shell having a centrally apertured base, a pole-piece fixed to said base, a second pole-piece movable in relation to said shell and projecting outside said apertured base, an insulating spool within said shell, a dish-shaped plate extending across the apertured part of said base, common means for securing both said spool and said plate to said base, a sleeve secured to and surrounding said second pole-piece, and fitting closely within said first-named pole-piece so that the latter acts as a guide-bearing for said second pole-piece and its sleeve, and means extending transversely of said second pole-piece for securing said sleeve thereto, said transverse means having end surfaces in direct contact with said first pole-piece, for magnetic continuity therewith.

2. In a solenoid, a magnetic shell having a pole-piece fixed thereto, a second pole-piece movable in relation to said shell, a sleeve secured to and surrounding said second pole-piece and fitting closely within said first-named pole-piece so that the latter acts as a guide-bearing for said second pole-piece and its sleeve, and means extending transversely of said second pole-piece for securing said sleeve thereto, said transverse means having end surfaces in direct contact with said first pole-piece, for magnetic continuity therewith.

JOSEPH W. ALLEN.
